United States Patent Office.

SAMUEL D. HOVEY, OF BROOKLYN, NEW YORK.

Letters Patent No. 93,823, dated August 17, 1869.

IMPROVEMENT IN RUBBER ERASERS.

The Schedule referred to in these Letters Patent and making part of the same.

To all whom it may concern:

Be it known that I, SAMUEL D. HOVEY, of Brooklyn, in the county of Kings, and State of New York, have invented certain new and useful Improvements in Pocket-Erasers; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to rubber used as an eraser of pen or pencil-marks; and

It consists in so arranging such rubber with a case that it can be shoved in or out at pleasure, and thus be carried in the pocket, without danger of soiling it, as hereinafter explained.

Figure 1 represents my improved device ready for use.

Figure 2 represents the same, attached to an ordinary wood lead-pencil.

Figure 3 represents the same closed, as carried in the pocket.

It has become customary, and is very convenient for business men, to carry in their pocket a small piece of vulcanized rubber, to be used as an eraser, the most convenient and approved form being that of a small roll. When thus used, the rubber, by being carried in the pocket, is very apt to become more or less soiled, and then, when used, it smears and soils the paper on

which it is used. It is to prevent this, and provide a nice article as a pocket-eraser, that my invention is intended.

In constructing my device, I first provide the rubber eraser, as represented by R of the drawings, and then provide for it a case, A, having a ring, B, connected to and operating a slide inside, the rubber being connected to and moving with the slide in the same manner that pen and pencil-cases are made, and as shown in the drawings.

This case A may be made of a size just sufficient to contain the rubber when drawn in, as shown in fig. 3, and extended in fig. 1, or it may be made longer, with its opposite end left open, also, so that it can be slipped on to the end of an ordinary wood lead-pencil, as shown in fig. 2.

The case may be made of metal, hard rubber, or any other suitable material, and in any desired style to suit the fancy.

An eraser thus made is admirably adapted to the purpose intended, and can be carried in the pocket, and kept clean and ready for use at any time.

Having thus described my invention,
What I claim, is—

A pocket-eraser, consisting of the case A, with the rubber R, arranged to slide therein, substantially as described, as a new article of manufacture.

SAMUEL D. HOVEY.
